UNITED STATES PATENT OFFICE

LEOLYN F. SPEAR, OF WESTFIELD, MASSACHUSETTS, ASSIGNOR TO GILBERT & BARKER MANUFACTURING COMPANY, OF SPRINGFIELD, MASSACHUSETTS, A CORPORATION OF MASSACHUSETTS

OIL BURNER

Application filed October 26, 1927. Serial No. 228,914.

This invention relates to improvements in oil burners.

The general class of oil burner, with which this invention is concerned, is one having a firepot or retort, into which the constituents of the mixture, oil and air, are separately introduced,—the mixture of these constituents being effected in the retort without the aid of mechanical atomizing devices. In burners

10 of this type, the oil is vaporized within the retort and the oil vapor is picked up by and mixed with, an incoming stream of air. The air flow is sometimes induced by natural draft but preferably by a fan or blower which

15 forces the air through the retort in order to secure a controlled draft, usually of relatively low pressure. Such burners, being dependent on vaporization of the oil, must be maintained hot enough at all times to effect

20 the vaporizing function. While the burner might be started and stopped and a separate source of heat employed for keeping the necessary parts of the burner hot during periods when the burner is not in operation, it is de-

25 sired to avoid the complications which would be necessary if this plan of operation were followed. With the burner of this invention, the plan adopted is to operate the burner continuously during the heating season at

30 either high or low rates according to whether or not heat is required from the heating plant with which the burner is associated. The burner operates at a low rate during idle periods of the heating plant and furnishes of itself the necessary heat to keep the parts hot enough for the vaporizing function.

One of the problems for which this invention offers a solution, relates to the maintenance of a satisfactory low fire in the burner.

35 Necessarily, it is of prime importance that the rate of oil consumption be kept exceedingly low. At the same time a controlled draft is necessary in order to secure a satisfactory flame. Reliance on natural draft is

40 unsafe and uncertain and is apt to result in a smoky fire and to cause excessive deposits of soot in the retort and in the boiler. Therefore, the fan is kept in operation during low fire as well as high fire. The fan, however,

45 50 preferably operates at the same rate on high

and low fire and, accordingly, unless means are provided to prevent, air in excess of requirements would be supplied to the low fire. The air tends to cool the retort and thus opposes the action of the flame, making it necessary to use a higher "low fire" or else suffer the disadvantages which ensue from excess air, such as excessive carbon deposits and a smoky and uncertain fire.

The invention has for an object the utilization of exhaust gases or products of combustion from the fire box, or other convenient source, in a manner such as to solve the above stated problem.

More particularly, the invention has for an object the provision of means which automatically come into play when the burner is shifted from high to low fire, to cut off, or at least substantially reduce, the supply of fresh air to the retort and to cause the retort to be supplied almost entirely with products of combustion, which may be taken, for example, from the firebox of the boiler.

The heating effect of these gases is utilized to aid the low fire in the work of maintaining the necessary parts of the burner hot during low fire operation. The gases aid the flame in its work instead of opposing it, as does the air. While the heating effect of the gases is the primary consideration, yet there is the added advantage that the gases tend, as is well known, to spread and diffuse the flame and prevent local overheating of the retort and associated parts. An exceedingly low rate of oil consumption on low fire can be secured and at the same time the burner can be kept hot so that, when later shifted to high fire, the full stream of oil will be readily vaporized and flooding of the retort will be avoided.

Another problem for which this invention offers a solution, relates to the vaporization of the oil, mixing of the oil with the air and burning the mixture in a retort or firepot without serious difficulties due to carbon deposits. Burners of this general type, as heretofore provided, have the disadvantage that carbon deposits are readily and rapidly formed. Also the action is not confined entirely to the retort but extends to the boiler

itself, wherefore frequent cleaning of both burner and boiler are required.

This invention has for another object the provision of a retort, together with an oil vaporizing and distributing means and an air directing means, all of which are of improved construction and specially designed with the object in view of producing a good mixture of the constituents and delivering a clean sharp flame into the boiler, without causing carbon deposits to such an extent as to necessitate cleaning more than once each season.

The primary characteristics are that the oil is vaporized to a large extent while out of direct contact with the incoming air stream; that this vapor is delivered to, picked up by, and mixed with the air stream before ignition occurs; that the burning stream of mixture is turned and returned, during its passage toward the outlet of the retort, to mix the leaner and richer portions of the stream; that the flame, as delivered from the outlet, is substantially uniform and homogeneous except that it is encompassed by a protecting envelope of leaner mixture; and that the leaner portions of the stream only are allowed to contact with and traverse the walls of the retort, thereby protecting such walls from the richer portions of the stream which tend to rapidly deposit soot and carbon.

There are many details, which contribute to the accomplishment of the above objects and these, as well as other objects, will appear in the following description and be pointed out in the appended claims.

The invention will be disclosed with reference to the accompanying drawings, in which—

40 Fig. 1 is a top plan view of an oil burner embodying my invention;

Fig. 2 is an elevational view, drawn to a small scale and showing in conventional form the manner in which the burner is installed in 45 a steam boiler;

Fig. 3 is a side elevational view, partly in section (taken along the line 3—3 of Fig. 1), of the burner;

Fig. 4 is a fragmentary cross sectional view 50 taken on the line 4—4 of Fig. 3 and illustrates the air damper, which is shown in closed position rather than in the open position shown in Fig. 3;

Fig. 5 is a front elevational view of the 55 burner;

Fig. 6 is a cross sectional view thereof taken on the line 6—6 of Fig. 1;

Fig. 7 is a sectional view of the solenoid operated oil valve;

Fig. 8 is a cross sectional view taken on the 60 line 8—8 of Fig. 6; and

Fig. 9 is a diagrammatical view illustrative of an electrical system for controlling the burner.

65 Referring to these drawings; the burner

includes a retort 10, which is adapted to be inserted through the fire box opening *a* of a boiler *b*, or the like, and to lie partially within the fire box *c* thereof. This retort has a flame outlet 11, formed in its front wall near the upper part thereof, and an inlet 12 for air and/or products of combustion, the latter being taken from the fire box *c*. The inlet 12 is formed by an extension 13 of rectangular cross section which extends rearwardly from the back wall of the retort near the upper part thereof. The retort 10 is provided with a marginal flange 14, which is adapted to abut the outer face of the usual hinged fire box door *d* and to be secured thereto, as by bolts 15. This door *d* is cut out to form an opening to receive the retort and, in addition, a rectangular opening 16 which is located centrally and immediately above the top wall of the retort. This top wall is normally closed but is provided with a removable cover 17, through which access may be had to the interior thereof when desired. By opening door *d*, i. e. swinging it on its hinges *d'*, the retort may be moved out of the fire box *c* and fire box door opening *a* so that cover 17 may be removed. An eccentric 18, mounted on a stud 19, secured to the top wall of retort 10, serves to hold cover 17 in place in an obvious manner.

Provisions are made for supplying air, together with products of combustion from fire box *c*, to retort 10, or for supplying the retort substantially entirely with the products of combustion. Such provisions include a fan which comprises a rotor 20 and a casing 21, and an electric motor 22, to the shaft 23 of which the rotor 20 is attached, all as indicated in Fig. 5. The casing 21 has a peripheral discharge passage 24 (Figs. 3 and 5), formed by an extension 25 of the fan casing, which passage initially extends downwardly and toward the retort and thereafter continues horizontally. This extension 25, as it approaches the retort, spreads out laterally on opposite sides, as best shown in Fig. 1 at 26, and finally terminates with a box-like end 27 (Figs. 3 and 5) of rectangular cross section. This end 27 fits over the described extension 13 of the retort and is suitably secured thereto, as by screws 28 (Figs. 3 and 4). Thus, the discharge passage 24 of the fan is connected to the inlet 12 of retort 10.

It will be noted that the retort, which in itself is supported from door *d*, serves to support the fan casing and that the latter is provided with a flange 29 (Fig. 5) to which the bed plate 30 of motor 22 is bolted. The fan and motor are not large or heavy and ordinarily can be suitably supported in the manner described. However, if desired, an auxiliary support may be had by connecting casing 21 to boiler *b* by a chain 31 (indicated conventionally in Fig. 2 and shown in part in Fig. 3) which chain is, or may be, attached

to an eyebolt 32, adjustably held by a wing nut 33 to a lug 34 on casing 21.

The intake to fan casing 21 is formed by a separate casing 35. This casing at one end flares out, as at 36 (Fig. 1) and terminates with a box-like end 37, similar in form to the end 27, except that it has no bottom wall (see Figs. 3 and 4) and except that its top wall 38 is made removable, being held in place by screws 39. The member 37 overlies and rests upon the member 27 with its open end directed toward and in closely adjacent relation with a wall of boiler *b*. The casing 35 also, to a limited extent, overlies and rests upon the casing 25 and is suitably secured thereto, as by a screw 40 (Fig. 1), which passes through a lug 41 on casing 35 and threads into casing 25. The other end of casing 35 terminates with a side opening which communicates with the fan casing 21 and is encompassed by a circular flange 42, secured by screws 43 to one end of fan casing 21. Located within the end 37 and secured, as indicated in Fig. 4, to the top wall of the end 27 is a member 44. The latter is bent to form, in conjunction with said top wall, a tunnel 45 which communicates with and forms an extension of the opening 16 in the fire box door.

It will thus be seen that the fan has an inlet 46, through which atmospheric air, pre-heated to some extent by contact with the walls of boiler *b*, enters and an inlet 45, through which products of combustion from fire box *c* enter. It is to be noted that this burner is not supplied with air from the ash pit, as is frequently customary,—the grate usually being suitably covered to prevent air from entering the fire box from below. It is also to be noted that an opening 47 (Fig. 5) is provided in that end wall of casing 21 which lies adjacent motor 22. Some such opening is, of course, necessary at this point to permit entrance of shaft 23 into the fan casing and to provide necessary clearance for the shaft. Accordingly, some air will enter the fan at this point and this arrangement has the advantage that such air tends to prevent the transmission of heat from the fan casing to the motor. Also, since the air cools these parts, it follows that the air which enters the fan is to some extent preheated.

The oil is supplied to the retort by gravity flow from any suitable source. In Fig. 2 I have indicated in conventional form a tank 48, of relatively small capacity, which is secured to the wall at a suitable level above that of the burner. Oil may be supplied to tank 48 manually or automatically by any suitable means and many expedients for this purpose are known to those skilled in the art. Tank 48 is equipped with a discharge pipe 49, which terminates adjacent to the burner and is connected thereto by a flexible pipe 50, so as to permit freedom of movement of the burner,

when door *d* is opened or closed. The pipe 50 as shown in Fig. 1, connects with a manually operable shut off valve 51. This valve, intended for use only when the burner is to be stopped, is normally open and oil flows through it into a strainer 52 of any suitable construction. The outlet of the strainer 52 is connected, as shown in Figs. 1 and 5, by pipe connections 53 to a valve casing 54.

Attached to this casing is a casing 55, containing a solenoid 56 (see Fig. 7), having a plunger 57 which reciprocates in a brass tube 58. This tube, which is connected to casing 54, has a closed upper end and functions to prevent leakage of oil from the valve casing 54 into the solenoid or associated parts. The plunger 57 at its lower end is provided with a needle valve 59, adapted to control the flow of oil from pipe 53 to a pipe 60, which is connected with the outlet of valve casing 54. An adjustable stop 61, threaded through the lower end of casing 54, is adapted to be engaged by the lower end of needle valve 59 to limit its downward movement. This stop is customarily set so as to prevent valve 59 from completely closing and so that only a very small opening is left to permit a relatively small flow of oil from pipe 53 to pipe 60. The stop 61 is therefore the adjustment for low fire. When solenoid 56 is energized, valve 59 is lifted to allow a large flow of oil through casing 54. The regulation of such flow, for "high fire" is however, controlled by other means.

The stop 61 is normally concealed and protected by a cap 62 threaded onto the lower end of casing 54. The solenoid casing 55 is connected, as indicated in Fig. 5, to a casing 63 which in turn is supported by and below bed plate 30. Casing 63 is adapted to contain electrical equipment which is used in connection with solenoid 56, such as a relay and transformer.

The pipe 60, as best shown in Figs. 1 and 5, connects the solenoid-operated valve to a safety shut off valve contained in a casing 64. This valve is a standard commercial article adapted to close on flooding of the burner. The valve has an operating stem 65 (Fig. 5) to which is fixed a weight arm 66 and a lever 67. A bucket 68 is suspended by a link 69 from lever 67 and is adapted to receive oil overflowing from retort 10, which oil is delivered to the bucket by a pipe 70. The bucket is enclosed by a two part housing 71, the upper portion of which is secured, as indicated, to valve casing 64 and provided with an opening to receive pipe 70. The bucket, when filled to a certain degree with oil, will turn shaft 65 in a clockwise direction and cause the safety valve to completely close. The weight arm 66 has a lug 66' which abuts a stop 72 on casing 64 and when positioned as shown, holds the valve fully open. A

shield 73, secured to casing 64, is provided as a partial housing for parts 66 and 67.

The safety shut off valve is connected by a pipe 74 to a valve casing 75 which contains a manually adjustable needle valve 76 (Fig. 3), adapted to control the outlet opening 77. Valve 76 has a part which extends outside casing 75 through a suitable stuffing box and is provided with a slotted end, whereby the valve may be turned by means of a screw driver. This valve controls the maximum flow of oil to retort 10 and thus the "high fire". A cap 78, threaded onto casing 75, covers and conceals the part by which valve 76 is adjusted. Valve casing 75 is open at its upper end so that oil can flow up and into the interior of a sylphon bellows 79, which is attached to casing 75 and serves as a closure for the otherwise open end thereof.

Oil passing through the outlet 77 enters a pipe 80 which leads into the retort 10. As shown, pipe 80 enters through the bottom wall of extension 13 and is connected to a special elbow fitting 81, which is disposed in passage 12 centrally between the side walls thereof. A suitable gasket 82 encompasses pipe 81 and is clamped between the bottom wall of extension 13 and the base of the elbow fitting 81,—the latter being secured to said wall by screws 83 (Fig. 1). A screw 84, passing through the top wall of extension 13, threads into elbow 81 and aids in preventing it from tilting. The elbow 81 terminates with an interiorly threaded hollow hub 85 (Fig. 3) which is adapted for connection to a combined vaporizing, distributing and baffle member.

The member, just referred to, is best shown in Figs. 3 and 6 and conveniently takes the form of a casting 86, which is supported from elbow 81. The casting extends substantially all the way across the retort from one side wall to the other, except for small clearance spaces 87, and also extends from a position closely adjacent the top wall of the retort downwardly,—forming a baffle by means of which the air entering through passage 12 is, for the most part, forced to pass downwardly toward the bottom and rear part of the retort and in under the lower edge of the baffle through the space 88. The upper edge of member 86 is held from contact with the top wall of the retort by lugs 89, leaving a passage 90, through which a part of the air stream may pass along and traverse the entire top wall of the retort, thereby tending to keep such wall and the cover 17 cool but more particularly serving for a more important purpose, later to be described.

In the upper and front part of member 86 is formed a pocket 91 which extends across from one side to the other of the member. This pocket is entirely closed at its front, ends, top and bottom but is only partially closed at the rear by a wall 92 which extends

from the bottom wall of the pocket upwardly but terminates short of the top wall. Thus, the lower part of pocket 91 forms a trough 93 and the upper edge 94 of wall 92 forms a weir over which oil may overflow from the trough. The wall 92, at its central part, is connected to the top wall of the pocket by a web 95 and on each side of this web, the upper edge of wall 92 is recessed, as at 96, so that the weir is slightly lower at the center than at the ends. This arrangement insures that more oil will flow downwardly in the center than at the sides of the retort and this is desirable because the air stream is denser at the center than at the sides due to the fanning out, as at 26, of the discharge tube 25 of the fan. Also, in case the edge 94 is not exactly level, oil will still flow over the center of the weir rather than wholly at one end, as would be the case if the weir were of uniform height throughout its length. A certain degree of leeway is afforded so that close accuracy in levelling the weir is not required.

The member 86 is secured to the hollow hub 85 by a cap screw 97 which passes centrally through the front wall of pocket 91, through the pocket, and through the central web 95, and threads into the hub. The head of screw 97 is drawn tightly against the front wall of pocket 91 and the end face of hub 85 is drawn against the web 95. The screw 97 is provided with an axial passage 98 leading from its threaded end inwardly toward but terminating short of the head. One or more radial passages 99, provided in screw 97, intersect passage 98 and afford communication between passage 98 and the interior of pocket 91, whereby oil may enter the latter.

It is desired to shield the pocket 91 from the direct action of the air stream so that, so far as possible air is kept from entering the pocket. The entry of air to such pocket, and the mixing of it with the oil therein, is not desired because it would then be possible for combustion to take place within the pocket. Combustion within the pocket is not desired because it would result in the formation of coke and tar deposits, which would soon fill up and choke the oil trough 93. To this end, the top and side walls of pocket 91 are extended rearwardly, as at 100 and 101, respectively, and a plate 102 (Fig. 8) is secured by screws 103 to the extension 100. The walls 100, 101 and plate 102 form a box-like shield for the pocket 91. A horizontal ledge 104, formed on the rear face of the back wall 92 extends toward plate 102 but terminates short of the same, leaving an outlet passage 105, commensurate in length with the length of trough 93. The hub 85 of elbow 81 passes through plate 103, and a circumferential flange 106 (Fig. 3) provided on the hub, lies closely adjacent the plate and makes it diffi-

cult for air to enter the pocket 91 by way of the space surrounding hub 85.

Any excessive accumulation of oil in retort 10 will pass out through a pipe 70' (Figs. 1 and 3) which connects with the described overflow pipe 70 through the intermediary of a suitable trap or liquid seal, indicated at 70².

The casing 25, in one of its flaring sides 10 26 is provided with an opening 107 (Fig. 1), which is normally closed by a cover 108. By opening this cover, one can insert a lighter 15 through the opening for the purpose of initially igniting the oil, thus avoiding the necessity of opening door *d* and removing cover 17.

Means are provided for shutting off substantially all of the air supply during those periods when the burner is operating on low fire. Such means comprises a damper 109 (Figs. 3 and 4) mounted on a shaft 110 which in turn is mounted at its ends in the upstanding walls of member 37. This damper is cut away, as shown at 111 so as to clear the tunnel 45, whereby when closed as shown in Fig. 4, the air inlet 46 is entirely closed while the tunnel 45 remains entirely open at all times. This damper is made to open and close at proper times automatically and any suitable mechanism may be used for this purpose. As shown herein, by way of illustrative example, the damper is operated by the change in pressure of the oil when the valve 59 is moved from low fire to high fire position 25 and vice versa. For example, the damper may be connected by a link 112 to one arm of a bellcrank lever 113, pivotally mounted on a stud 114, which is secured to a post 115 (Fig. 5), the latter being secured to casing 35 by a screw 116. The casing 35, at a point adjacent the fan, has a depending tubular part 117 which is axially alined with the bellows 79, heretofore described, and a link 118, pivotally connected to the other and relatively short arm of bellcrank 113, extends downwardly through the opening in part 117. The lower end of link 118 is adjustably connected, as indicated in Fig. 3, to a bracket 119 secured to the upper and closed end of bellows 79. The latter is enclosed by a cylindrical housing 120, secured at its lower end to valve casing 75. Housing 120 is connected to the tubular part 117 by a sleeve 121, which is secured to said part for convenient detachment, as by a screw 122 (Fig. 5). By detaching screw 122, the sleeve 121 will slide down on casing 120 and expose the connection between parts 118 and 119, thereby allowing access thereto as well as to the upper end of bellows 79. An inwardly turned, circumferential flange 123 is formed on the upper end of casing 120 and a conical spring 124 acts between this flange and the top of bellows 79, tending to force the latter downwardly and close damper 109. In Fig. 4, it is as,

sumed that the full flow of oil is passing to the burner and that the bellows is held in the position shown by the pressure of such oil, whereby the damper is open. When, however, the solenoid operated valve is 70 moved to reduce the flow of oil for a low fire, the pressure of the oil in bellows 79 materially drops and spring 124 then functions to collapse the bellows and close the damper. Thus, when the burner operates on low fire, 75 damper 109 is closed and when it operates on high fire it is open. Also, the arrangement is such that a shift from one condition to another automatically operates the damper. It is to be noted that the damper is either 80 open or closed and never remains in any intermediate position. Also, that the movement of the damper from one position to another is rapid, being controlled by and caused to move substantially in unison with, the 85 solenoid-operated oil valve.

The particular manner of controlling the operation of the oil burner is not an important part of this invention. Moreover, the burner may be used with various control 90 and safety devices known in the trade. However, an example of one suitable scheme of control is shown schematically in Fig. 9. The fan motor 22 is connected directly to the line wires 126, which may be the usual 95 commercial lighting or power circuit. The fan 21 is intended to run continuously during the heating season, wherefore the motor 22 is not provided with any control except for a manually operable switch, such as 127. 100 The solenoid 56, by means of which the flow of oil to the burner is controlled, is also connected to the line wires 126 but through the intermediary of a switch 128, which is adapted to be operated by an electromagnet 129. 105 The latter is included in series with two thermostatically operated switches 130 and 131 in a low voltage circuit 132, supplied by a transformer, the primary and secondary windings of which are designated 133 and 134, respectively. The winding 133 is connected to the line wires 126. The thermostat switch 130 is intended to respond to room temperature, opening when the temperature exceeds a predetermined degree. The thermostat switch 131 is intended to respond to the temperature of the medium which is being heated by the furnace or boiler. For example, switch 131 may respond to steam temperature and be arranged, as a safety device, to open when such temperature becomes excessive. The control mechanism actually used is rather more elaborate than that shown in Fig. 9 but it functions in the same general manner as above set forth, and the conventional illustration has been adopted on the score of simplicity.

The burner, as has been set forth, is intended to operate continuously during the heating season. Consequently, it is hardly 135

necessary to provide an ignition means as on the few occasions when the burner has to be lighted, it may be accomplished manually. It is, however, obvious that any suitable automatic ignition means may be applied to the burner should it prove necessary or desirable. In lighting the burner manually, a torch of asbestos soaked with oil may be used, being inserted through opening 107 into the retort 10 and in close proximity to the rear face of baffle 86. Previous to the insertion of the torch, oil is allowed to flow into trough 93 until it is filled and overflows down the baffle plate in to the retort. To accomplish this, the valve 51 is opened and switch 127 is closed. Assuming that both thermostat switches 130 and 131 are also closed, motor 22 will be operated and solenoid 56 energized. Thus, the valve 59 will be opened to allow a full flow of oil to trough 93. A short interval, say about fifteen seconds, of such operation will suffice to supply the necessary oil for starting. Switch 127 is then opened, causing motor 22 to stop and allowing valve 59 to close down to minimum flow position. Damper 109, which opened when valve 59 was opened, also closed when that valve is moved to low fire position. Having supplied the retort with sufficient oil for starting, by the above described or any other suitable method, the torch is applied, as described, to ignite the oil in retort 10 while the valve 59 and damper 109 are in low fire position. The oil burns by natural draft, sufficient air entering through hole 107. The oil burns off the baffle plate 86 and in the retort and the heat therefrom, as well as that from the torch, heats the baffle 86 and the walls of trough 93. Eventually, usually in less than a minute, oil will be vaporized in the trough and emitted from outlet 105, where it is ignited. As soon as vapor is thus emitted and ignited, the lighting torch is withdrawn, cover 108 applied and switch 127 again closed, thereby starting the fan in operation and opening solenoid valve 59 and damper 109. The burner is then operated under high fire conditions until the retort and the baffle member are thoroughly heated, after which the burner will be allowed to continue in automatic operation (so long as switch 127 is left closed), running at either high or low fire as controlled by the thermostat switches or either of them.

The normal operation of the burner will now be described. Oil is delivered to trough 93 and air to inlet passage 12 at relatively low pressure. For example, the oil pressure may be a matter of ounces and the air pressure a fraction of an ounce. Assuming that the thermostat switches are closed, valve 59 will be positioned to allow a full flow of oil and damper 109 will be open. Fan 20 is always in operation and at constant speed. Air, preheated to some extent by contact

with the boiler, enters at 46 and mingles with a stream of products of combustion entering at 45 whereby the air is further pre-heated by the heat exchange between the two constituents of the stream drawn into the fan. The fan serves to mix these constituents and thus air, diluted to a certain predetermined degree with the products of combustion, is delivered to inlet 12 of the retort. The entering air and gases are hot and therefore in good condition to mix with the oil vapor.

The action in the retort is to vaporize the oil and mix the vapor to a considerable extent with the incoming stream of air and gases prior to ignition. The trough 93, when valve 59 is wide open, is filled with oil which is kept boiling by the heat of the walls thereof. Oil is therefore vaporized in the trough and the vapor is emitted at outlet passage 105. Some oil will also flow over weir 94 and such oil clings to the walls, following down the front edge of ledge 104, inwardly along its bottom face and thence downwardly along, and following the contour of, the baffle 86. Such oil, as thus flows onto the baffle, while distributed across the baffle, is in greatest volume near the central part thereof, where the air stream is densest, as has been explained. The baffle, being hot, the oil flowing downwardly on the rear face thereof is vaporized and ordinarily all vaporized before it reaches the lower edge of the baffle. That is, under normal conditions, and so far as can be seen, no oil drips from the bottom edge of baffle 86. If oil does drip from such edge, then it will be picked up by and carried along with the stream passing below such edge. No deposit of carbon is found on the bottom of the retort below the lower edge of the baffle as would be the case if unvaporized oil lodged there and burned. It should be noted that the fan may be speeded up and the oil flow increased if the burner is required to furnish more heat. When the burner is thus operated more oil will overflow from trough 91 and flow down on baffle 86. Then oil does drip from the lower edge of the baffle but it is picked up by and carried along with the stream as aforesaid.

The air and gases, entering at 12, are for the most part caused to pass downwardly and to sweep past outlet passage 105 and to pass along the rear face of baffle 86, thereby picking up the oil vapor and mixing with the same. The region in back of baffle 81 and down to about the level indicated by the dot-dash line α is one in which preliminary mixing takes place, during high fire operation. Ignition occurs at about the region indicated by the line α although the parts of the flame may be seen to flicker back and forth between this line and outlet 105 due to the burning off the baffle 86 of unvaporized oil. The stream of mixture passing down in back of

plate 86 will be found richest adjacent the plate and relatively lean adjacent the back wall of the retort. Also the mixture adjacent the sides of the retort is lean since less oil is emitted at the sides than in the center. Thus, the sides and back of the retort are traversed by the leaner portions of the mixture and in this way kept relatively free from carbon deposits. As the now burning stream turns 10 at right angles to pass in under the lower edge of the baffle, further mixing may take place here, especially on high speed operation when the stream picks up oil dripping from the lower edge of the baffle and carries the same 15 forwardly. The stream passing along the bottom wall of the retort is nevertheless lean in that portion which moves adjacent to such wall, whereby the latter is kept relatively free of carbon deposits. So also, when the stream 20 strikes the lower and semi-circular part of the front wall or nose of the retort, the lean portion of the stream lies adjacent to the retort wall. This nose is extremely hot and any unvaporized oil carried forwardly by the 25 stream will burn before it leaves the nose. The leaner part of the stream, being now well heated aids in the burning of oil which reaches the nose and also in burning off and preventing accumulations of carbon. The 30 stream is turned by the semi-circular wall, thrown back toward the front face of baffle 86, and caused to roll around in the retort to a certain extent to mix the lean and rich parts of the stream, which is finally thrown 35 forwardly toward and then downwardly out of the outlet 11. A substantially homogeneous mixture is obtained at this outlet except for the edges of the stream which are still somewhat leaner than the mixture in the body 40 of the stream. The stream of air and gases, unmixed with oil vapor, passing through passage 90 and across the top wall of retort 10, serves to keep said wall somewhat cooler and to prevent the formation of carbon deposits 45 thereon. Such last named stream functions like an air curtain for the described purpose and also supplies additional air to the flame for combustion. The stream, as emitted from outlet 11, is in the form of a rich mixture 50 surrounded by an envelope of leaner mixture. The flame emitted is clean and sharp, due to the thorough mixing, and is not of such a nature as to be particularly liable to deposit soot in and dirty up the boiler. Frequent 55 cleaning of the retort and boiler is therefore not necessary.

All walls of the retort 10 are traversed by the leaner portions of the stream, as above described, and the purpose of this arrangement is to prevent carbon deposits in the retort. Carbon will form on both faces of baffle 86. Such carbon as forms on the front face of the baffle has been found to be more of a sooty nature than of the hard coke-like 65 variety. Coke-like deposits would have to

be scraped off but the sooty deposit, after accumulating to a certain extent falls off in flakes and is picked up by the stream and burned. On the rear face of the baffle, deposits of a tar like nature will form. The lighter fractions of the oil will be distilled off leaving the heavy constituents on the plate. These deposits burn off to some extent during low fire operation. No carbon is ordinarily formed in the pocket 91 nor in trough 70 93 during high fire operation for no burning takes place therein. The idea is to confine the carbon deposits to the baffle which is easily removable for cleaning.

Assuming now that thermostat switch 130 80 opens, the solenoid 56 will be deenergized and valve 59 will drop to restrict the flow of oil. The pressure of oil on bellows 79 is then relaxed and damper 109 closes under the influence of spring 124. The fan, however, continues to run at the same speed but now delivers to the retort products of combustion. That is, for the most part, only gases from fire box *c* are supplied to the retort although, as has been explained, some air will leak in, 90 as around the shaft 23. The cool air entering at this point is an advantage on low fire operation because since fan 20 draws almost entirely from fire box *c*, the fan tends to become very hot and it is desirable to minimize 95 the transmission of this heat to the motor 22. The provision for supplying the retort, so far as is feasible, entirely with gases from fire box *c* during low fire operation is extremely important because of the material 100 heating effect on the retort and baffle member. The gases aid very greatly in keeping these parts hot and in readiness to quickly vaporize oil, when the valve 59 is later opened to high fire position. Less oil needs to be burned on 105 low fire to maintain the retort and associated parts at the desired temperature and, of course, this makes for economy in oil consumption. Also, it makes it practical to operate on the high-low fire principle, where- 110 as it might not be commercially feasible if a relatively heavier consumption of oil on low fire were necessary because the low fire periods are idle ones in the sense that heat is not then required from the heating plant. The heat 115 from the low fire is, however, useful in keeping the boiler warm and in readiness to steam quickly when steaming is required.

Considering now the action in the retort when the valve 59 is shifted from high to low fire position, the trough 93 which was full of oil when the valve shifted, becomes gradually depleted by vaporization. Finally, the oil which on low fire is fed virtually only drops by drop, can be heard to drop on the bottom 120 of the trough and sizzle on the bottom wall which is still hot. Oil vapor only is now emitted at 105 and this vapor, as before, mixes with the incoming gases but burns near 125 the outlet 105. The flame then plays directly 130

on the baffle plate and keeps it hot and burns off carbon formed on the rear face thereof during high fire operation. The shifting back, on low fire, of the point of ignition is important because, if ignition took place on low fire at the same point that it does on high fire, there would be little heating of the baffle plate and less heating of the walls of the oil trough. After the trough has been depleted of oil, it becomes somewhat cooler and the vaporization of oil is retarded. Consequently, oil begins to accumulate in the trough so that a supply will be available when the burner is later shifted to high fire.

This accumulation of oil is also important as preventing the formation of carbon which might otherwise occur if the drop by drop feed of oil to the warm bottom wall of the trough were continued. That is, a little pile or mound of carbon would in time build up in under the outlet of the oil pipe. As the burner normally operates, carbon accumulates only in the trough and on the baffle. The carbon on the front face of the latter for the most part falls off and is burned, as above described. The carbon deposits in trough 93 and on the front face of the baffle are slow in forming and usually cleaning is required only once each season. The mounting of the baffle is such that it may be removed for cleaning very readily. It is simply necessary to swing the burner out of the fire box, remove cover 17, and remove cap screw 97, after which the baffle member may be withdrawn. By then removing the plate 102, access may be had to the trough for cleaning.

The idea of mixing products of combustion with the air supplied to an oil burner is, of course, well known and it is known that this expedient tends to reduce the noise of the burner and, by diluting the air stream, to retard combustion and diffuse the flame. In the present burner, I make use of this expedient for the usual reasons on high fire operation. That is, during operation of the burner on a full flow of oil, a certain volume of products of combustion is mixed with a certain volume of air and the proportions of the two constituents are maintained constant.

While deriving the usual and known advantages from the use of the products of combustion during full operation of the burner, I also make use of them in a novel manner as an aid to the solution of a special problem, which relates entirely to low fire operation. Having as a starting point a vaporizing burner of the fire pot type, without any mechanical atomizing of the oil, it is essential that certain parts in the fire pot or retort need to be kept hot enough for the vaporizing function. This means that the burner must operate continuously, although at times at a reduced rate. With the stated type of burner, it is also essential to have a controlled draft. That is, it is not safe to

rely on natural draft even for low fire because unless the draft happens to be just right, a smoky and sooty fire results. To operate a burner of this type on natural draft means that one is thrown entirely upon the mercy of the elements for the air supply and the results are at best uncertain and for the most part quite unsatisfactory. I have found it necessary to maintain a high velocity stream in the retort on low as well as high fire in order to avoid smoky, sooty flame. Therefore, the fan is arranged to run continuously and without change of speed during low fire operation.

The whole difficulty with this scheme comes entirely on low fire operation of the burner. To supply the retort with fresh air, or air mixed with gases from the fire box, in the same manner as on high fire operation will not do. Too much air will be delivered for the volume of oil which it is desired to consume. While this arrangement will work if enough of a low fire is used, it means heavier consumption of oil during periods when no heating from the boiler is needed. It is, of course, essential to keep the oil consumption on low fire as low as possible and a commercially satisfactory low rate cannot be had if air and gases are supplied to the low fire in the same way that they are to the high fire. The air would cool the retort and associated parts at a time when it is essential to keep these parts hot with the lowest possible consumption of oil. The air, in excess, would not only prevent one from getting a good low fire but it also would work a serious handicap by its cooling effect.

Therefore, I have provided the damper 109 which cuts off, so far as is practical, all air from the retort during low fire operation and causes the fan to supply hot gases thereto. These gases enable a high velocity stream to be maintained through the retort without getting excess air. The gases also aid the low oil flame in maintaining the vaporizing heat instead of opposing the action, as would the air, whereby the oil consumption on low fire may be cut down to a very low limit, say drop by drop, in much the same manner that oil would flow from a lubricating oil cup. The gases also tend to diffuse the low flame, whereby it is spread over a greater area, the better to maintain the parts warm. Also, the fan and its intake and discharge tubes are kept hot so that when the burner is again shifted to high fire, there is no sudden inrush of cold air into the retort. The full stream of air, admitted at such time, will be pre-heated by the hot fan casing and intake and discharge tubes and delivered in proper condition. Danger of flooding of the retort at this time is thereby eliminated.

The damper 109 has no function in the normal operation of the burner and, except for the low fire condition, could be omitted. It

is arranged to close off the entrance of air, on low fire operation, so that the heat from the burner may be retained and utilized to keep the parts hot during the intervals when heat from the boiler is not needed. As a practical matter the fan and its intake and discharge tubes are kept so hot on low fire operation that they are uncomfortable to the touch. Thus, the damper 109 solves a most important problem in a burner of this type and renders practical, and commercially feasible, a type of burner that otherwise would not be because of the difficulty in maintaining a satisfactory low fire or, if this is accomplished, a satisfactorily low rate of oil consumption on low fire.

The invention affords a satisfactory burner of the vaporizing and fire pot type. The difficulties due to carbon deposits in the burner and the tendency to cause dirty condition of the boiler have been overcome as well as the problem of low fire operation. Also, there are no pilot or ignition complications or difficulties incident thereto. A very large percentage of the troubles developing in connection with oil burners have been due to difficulties with ignition. By operating the burner continuously the ignition means and the ensuing troubles can be eliminated. The invention has been disclosed herein, in an embodiment at present preferred, for illustrative purposes but the scope of the invention is defined by the appended claims rather than by the foregoing description.

35. What I claim is:

1. In an oil burner, a retort having an outlet adapted to communicate with a firebox and a passage for the admission of air to the retort, means for supplying oil to the retort at either a high or a low rate, a valve controlling the inflow of air to said passage, a connection through which combustion products of the firebox may be delivered to the retort, and means for closing said valve and causing said retort to be supplied with products of combustion when the oil supply is changed from the high to the low rate.

2. In an oil burner, a retort having an outlet adapted to communicate with a firebox of a boiler or the like and a passage for the admission of air to the retort, means for supplying oil to the retort including means for controlling the rate of flow and maintaining it at either a high or a low rate, a valve controlling the inflow of air to said passage, a connection through which products of the firebox may be delivered to the retort, and means automatically operable when said controlling means effects a change from high to low rate of flow for closing said valve and causing the retort to be supplied with the products of combustion.

3. In an oil burner, a retort having an outlet adapted to communicate with a firebox of a boiler or the like and a passage for the ad-

mission of air to the retort, means for supplying oil to the retort including means for controlling the rate of flow and maintaining it at either a high or a low rate, a valve controlling the inflow of air to said passage, a connection through which products of the firebox may be delivered to the retort, and means automatically operable by the variation in oil pressure in said oil supply means when said controlling means effects a change from high to low rate of flow for closing said valve and causing the retort to be supplied with products of combustion.

4. In an oil burner, a retort having an outlet adapted to communicate with a firebox of a boiler or the like and an inlet passage communicating in part with the atmosphere and in part with the firebox for the purpose of receiving products of combustion therefrom, a valve for controlling the inflow of air to said inlet passage, connections for supplying oil to the retort, a valve movable from one position in which it permits a relatively small flow of oil to the retort to another position in which it permits a larger flow of oil thereto for the normal fire, and means operable by variations in pressure of the oil in said oil supply connections for closing the air valve when the oil valve is in the first named position and opening the air valve when the oil valve is in the last named position.

5. In an oil burner, a retort having an outlet adapted to communicate with a firebox of a boiler or the like and an inlet passage communicating in part with the atmosphere and in part with the firebox for the purpose of receiving products of combustion therefrom, a valve for controlling the inflow of air to said inlet passage, connections for supplying oil to the retort, a valve movable from one position in which it permits a relatively small flow of oil to the retort to another position in which it permits a larger flow of oil thereto for the normal fire, and means automatically operable by movement of the oil valve from the second to the first named position for closing said air valve and by movement of the oil valve from the first to the second position for opening said air valve.

6. In an oil burner, a retort adapted to be mounted on the door of a firebox of a boiler or the like and having an outlet to direct the flame into the firebox and an inlet extending through said door, a fan having a discharge conduit connected to said inlet and having an intake conduit extending toward and terminating with its air receiving end closely adjacent said door, said door having a passage therethrough for supplying gases from the firebox to said intake conduit, a valve to close off the inflow of air through said end, means for operating said fan continuously, oil supply means including a valve which at

all times permits a small flow of oil to the retort and is movable to permit a larger flow, automatic means for operating said oil valve, and means for closing said air valve when the oil valve is moved to cut down the flow of oil and for opening the air valve when the oil valve is moved to increase the flow.

7. In an oil burner, a retort having an outlet adapted to communicate with a firebox of 10 a boiler or the like and an inlet passage communicating in part with the atmosphere and in part with the firebox for the purpose of receiving products of combustion therefrom, a valve for controlling the inflow of air to 15 said inlet passage, connections for supplying oil to the retort, a valve movable from one position in which it permits a relatively small flow of oil to the retort to another position in which it permits a larger flow of oil thereto 20 for the normal fire, and means responsive to the rate of flow of oil for closing the air valve when the oil valve is in the first named position and opening the air valve when the oil valve is in the last named position.

25 8. An oil burner, comprising, a retort having in substantially opposed relation an inlet passage for air and an outlet passage for the flame and being closed except for said passages, means for delivering air to said inlet passage, a baffle member in said retort opposing direct flow from the inlet to the outlet and serving to turn the major portion of the air stream and in conjunction with the walls of the retort to cause the stream to traverse a tortuous path in order to reach said outlet, said baffle member having a pocket therein in which oil is vaporized while out of contact with the air stream and a passage leading from the pocket through which unignited oil vapor is delivered to the entering air stream, and means for supplying oil to said pocket.

40 9. An oil burner, comprising, a retort having in substantially opposed relation an inlet passage for air and an outlet passage for the flame and being closed except for said passages, means for delivering air to said inlet passage, a baffle member in said retort opposing direct flow from the inlet to the outlet and serving to turn the major portion of the air stream and in conjunction with the walls of the retort to cause the stream to traverse a tortuous path in order to reach said outlet, said baffle member having associated therewith an oil trough shielded from the incoming air stream and an outlet passage for the vapors from the trough leading towards that face of the baffle which is engaged by the incoming air stream, and means for delivering oil into said trough.

45 10. An oil burner, comprising, a retort having in substantially opposed relation an inlet passage for air and an outlet passage for the flame and being closed except for said passages, means for delivering air to said in-

let passage, a baffle member in said retort opposing direct flow from the inlet to the outlet and serving to turn the major portion of the air stream and in conjunction with the walls of the retort to cause the stream to traverse a tortuous path in order to reach said outlet, said baffle member having associated therewith an oil trough shielded from the incoming air stream and an outlet from the rear of the trough leading towards that face of the baffle which is engaged by the incoming air stream, the front and bottom walls of said trough projecting beyond the other face of the baffle toward said outlet passage so as to be exposed to and heated by the burning mixture as it travels toward said outlet, and means for feeding oil to said trough.

50 11. In an oil burner, a retort having an inlet for air in the upper part of its rear wall and an outlet for the flame in the upper part of its front wall, a baffle member supported within the retort and interposed between the inlet and outlet for the purpose of turning the air stream downwardly, said baffle extending from the top wall of the retort downwardly towards but terminating short of the bottom wall leaving a passage through which the stream passes toward the front wall of the retort, said baffle extending across the retort from one side wall to the other, the lower part of the front wall of the retort being approximately semi-cylindrical to turn the stream back towards the baffle and terminating with an upper edge defining one wall of the outlet, the top wall of the retort being projected forwardly beyond said edge and curved downwardly to turn the stream thrown forwardly by the baffle toward the outlet, the lower edge of said downwardly curved wall defining the opposite wall of said retort.

55 12. In an oil burner, a retort having an inlet for air in the upper part of its rear wall and an outlet for the flame in the upper part of its front wall, a baffle member supported within the retort and interposed between the inlet and outlet for the purpose of turning the air stream downwardly, said baffle extending from the top wall of the retort downwardly towards but terminating short of the bottom wall leaving a passage through which the stream passes toward the front wall of the retort, said baffle extending across the retort from one side wall to the other, the upper edge of said baffle being spaced from the top wall of the retort so as to leave a restricted passage through which a part of the incoming air stream can pass directly from the inlet to the outlet in a path adjacent the top wall of the retort, the lower part of the front wall of the retort being approximately semi-cylindrical to turn the stream back towards the baffle and terminating with an upper edge defining one wall of the outlet, the top wall of the retort being projected

forwardly beyond said edge and curved downwardly to turn the stream thrown forwardly by the baffle towards the outlet, the lower edge of said downwardly curved wall defining the opposite wall of said retort.

13. An oil burner, comprising, a retort having an inlet passage for air leading into the upper part of the retort near its back wall and an outlet passage for the flame leading from the upper part of the retort near its front wall, a baffle member extending between the side walls of the retort and interposed between said passages to turn the air stream downwardly, said baffle member depending from the top wall of the retort towards but terminating short of the bottom wall leaving a passage through which the down-turned stream can pass to reach the outlet, said baffle member constructed to afford a passage of restricted area through which air may pass directly from the inlet to the outlet, said baffle member having a pocket therein, means for supplying oil to said pocket, and means for supplying air to said inlet passage, said baffle having a passage leading from said pocket to the rear face thereof arranged to distribute oil crosswise of the baffle member.

14. An oil burner, comprising, a retort having an inlet passage for air leading into the upper rear portion of the retort and an outlet for the flame leading from the upper front portion of the retort, a baffle interposed between said passages and depending from the top wall toward but terminating short of the bottom wall of the retort, said baffle near its upper portion being hollow to form an oil trough which extends crosswise of the retort and is completely enclosed except along its rear side wall, a shield spaced rearwardly from the rear side wall of the trough to direct the entering air stream from said trough and affording between it and said rear side wall a downwardly directed outlet passage, and an oil supply pipe connected to the baffle to deliver oil into said trough, said rear side wall forming a weir over which oil may overflow from the trough and be distributed over the rear face of said baffle.

15. An oil burner, comprising, a retort having an inlet passage for air leading into the upper rear portion of the retort and an outlet for the flame leading from the upper front portion of the retort, a baffle interposed between said passages and depending from the top wall toward but terminating short of the bottom wall of the retort, said baffle near its upper portion being hollow to form an oil trough which extends crosswise of the retort and is completely enclosed except along its rear side wall, a shield spaced rearwardly from the rear side wall of the trough to direct the entering air stream from said trough and affording between it and

70 said rear side wall a downwardly directed outlet passage, and an oil supply pipe connected to the baffle to deliver oil into said trough, said rear side wall forming an oil distributing weir which is lower in the center than at the ends.

16. An oil burner, comprising, a retort having an inlet passage for air leading into the upper rear portion of the retort and an outlet for the flame leading from the upper front portion of the retort, a baffle interposed between said passages and depending from the top wall toward but terminating short of the bottom wall of the retort, said baffle near its upper part having an oil receiving chamber with an outlet therefrom to the rear face of the baffle, an oil supply pipe terminating near the rear upper part of the retort with an end on which said baffle is supported, a screw passing through the front face of the baffle and across said chamber and threaded into the end of said pipe, said screw having a passage therein connecting said pipe and chamber, the upper wall of the retort having an opening therein through which access may be had to said screw and through which the baffle may be removed, and a cover normally closing the last named opening.

95 In testimony whereof I have affixed my signature.
